[57] ABSTRACT

A punched paper tape controlled electrical control system for operating solenoids to release articles from gravity storage lanes in a warehouse onto a conveyor by which they are conveyed to an output station. The tape controls release of the articles so that they will exit the storage racks, one article per conveyor increment, in a predetermined order. The tape contains drop data for controlling dropping of articles from storage lanes, and shortage data for controlling a printer to print the bay, lane and serial number of an article if a photocell detector fails to detect exit thereof. The tape also contains control data for controlling purge of an order, that is, completion of an order without starting the partially overlapping next order punched on the tape. The tape further contains other control data for operation of the system. The system operation is synchronized by means of a rotary cam switch preferably driven by the conveyor to control the time of dropping of articles and checking for shortage at the photocell detector.

TAPE CONTROLLED ORDER PICKING SYSTEM

BACKGROUND OF THE INVENTION

Order picking systems have been known. While these have been useful for their intended purposes, they have been either manually controlled or have not included the features of complete separation from the apparatus that prepares the information bearing media, automatic printing of shortages, etc. This invention relates to improvements thereover.

SUMMARY OF THE INVENTION

This invention relates to an electrical control system for controlling picking of articles from a warehouse to fill an order.

An object of the invention is to provide an improved electrical control system run by information bearing media such as punched tape that may be prepared beforehand by and during any idle time of a general purpose computer and manually inserted in such control system reader when it is desired to operate the same.

A more specific object of the invention is to provide an improved electronic control system controlled by an information bearing medium for automatically controlling the picking of an order of articles from a warehouse, and for printing shortages to identify articles that do not exit.

Another specific object of the invention is to provide an improved logic system controlled by an information bearing medium for automatically controlling the picking of articles of an order from gravity chutes or lanes of a warehouse, and for purging the system of articles of an order without starting the next order partially overlapping on the medium, and for reversing the reader to the beginning of such next order when such next order is subsequently picked.

Another specific object of the invention is to provide an improved logic system controlled by an information bearing medium for automatically controlling the picking of articles of an order from selected bays and lanes of a warehouse that is partly self-checking by inhibiting the drop if there is an uneven number of frames of drop data, bay and lane.

Other objects and advantages of the invention will hereinafter appear.

BRIEF DESCRIPTION OF THE DRAWINGS

FIGS. 1a and 1b arranged in horizontal alignment show a block diagram of the tape controlled order picking logic system;

FIG. 2 is a schematic illustration of a group of bays each having a number of lanes, a conveyor, and a light beam and photocell exit detector;

FIG. 3 is an illustration of a section of punched paper tape showing frames of information codes and control codes thereon;

FIG. 4 is a graph showing rotary cam switch pulses used to control the instants of dropping and shortage checking;

FIGS. 5a and 5b arranged in vertical alignment show a flow diagram of the mode programmer shown in detail in FIG. 8;

FIGS. 6a, 6b and 6c arranged in vertical alignment show a flow diagram of the functional programmer shown in detail in FIGS. 9a - b;

FIGS. 7-26 show circuit diagrams of the details of the logic system as follows:

FIG. 7 is the console manual controls and purge logic;

FIG. 8 is the mode programmer shown in flow diagram form in FIG. 5a-b;

FIGS. 9a and 9b arranged in vertical alignment show is the functional programmer shown in flow diagram form in FIG. 6a-c;

FIG. 10 is the clock that produces A and B clock pulses for operation of the system;

FIG. 11 is the tape reader, its switching logic, and forward and reverse drive logic;

FIG. 12 is the leader data control character and drop data recognition logic;

FIG. 13 is the shortage data recognition logic;

FIG. 14 is the rubout code recognition logic;

FIG. 15 is the start of new order drop code, leader code, and start of new order shortage code recognition logics;

FIG. 16 is a group of set-reset memory logics;

FIGS. 17a and 17b arranged in vertical alignment show the tape reader input shift registers logics;

FIG. 18 is the multiplex (MPX) input logics that translate group and bay codes (binary octal) into selection codes to select one group from SMO-4 and one bay from BSO-7 in that group;

FIG. 19 is the multiplex (MPX) input logics that translate lane codes (binary octal) into selection codes to select one lane from forty lanes;

FIG. 20 is an inhibit logic that prevents selection of either a group of bays or a lane of a number higher than is provided in the system;

FIG. 21 is a gating logic for gating the drop codes from the shift registers in FIG. 17a-b at the proper time;

FIGS. 22a and 22b arranged in vertical alignment show the printer input logics and shift registers;

FIG. 23 is the SCR firing pulse circuit that controls the energization instant of the drop solenoid in FIG. 26;

FIG. 24 is the multiplex (MPX) circuit for one group (MPXO) of eight bays, provision being made for four additional MPX's like this for the additional groups MPX1-4, and controlled by the input logics of FIGS. 18 and 19;

FIG. 25 is the matrix (MTX) circuit for forty lanes in one bay (Bay O), provision being made for eight MTX's like this (0-7, 10-17, etc.) per group of bays times five groups (0-4), or a total of forty MTX's, and controlled by the lane selection relays of FIG. 24; and

FIG. 26 is the drop solenoid circuit for one bay of forty lanes, and controlled by the matrix relays of FIG. 25 and the SCR drop pulses from FIG. 23.

DESCRIPTION OF THE PREFERRED EMBODIMENT

An order picking system as shown schematically in FIGS. 1a-b and 2 comprises a logic circuit system (FIG. 1a-b) for controlling dropping of articles from gravity lanes, logging shortages, etc., and a warehouse consisting of inclined, gravity controlled, storage racks (FIG. 2) with automatic release mechanisms at the lower end of each lane by which a single article can be released from the lane onto a gathering conveyor. Proper control of the system is accomplished by releasing articles from the various lanes so that the articles will exit the storage area on the conveyor, one article per belt increment (space between two pushers P), with the articles in a predetermined order, this order being determined

55
60
65

by an information medium such as a punched paper tape.

For exemplary purposes, the storage area has five groups of bays MPX0-4, each having eight bays, B0-7, B10-17, B20-27, B30-37 and B40-47, respectively, and each bay having forty lanes L0-7, L10-17, L20-27, L30-37 and L40-47, as shown in FIG. 2. Five groups times eight bays times forty lanes provides 1600 lanes. As will hereinafter appear, the logic system is readily adaptable to more or less lanes.

A conveyor increment consists of 1.5 seconds of conveyor travel. Therefore, one article will exit the storage area each 1.5 seconds except where spaces are deliberately introduced. One control function of the logic system is to verify that an article does exit (breaks a light beam to a photocell PC in FIG. 2) each 1.5 seconds and, if it does not, to print an identification (bay, lane and serial number) of this shortage item.

The system is controlled by a punched paper tape on which the dropping sequence has been arranged to take into consideration the travel time between the storage lanes and the exit point where the shortages are checked at the photocell. As shown in FIG. 2, if it takes three seconds for an article to move out of the storage area, the identification (shortage data) for the article is read from the tape three seconds after the drop code is read. Thus, if the article exits, the shortage data is ignored. If the article does not exit, the shortage data is printed.

As shown in FIG. 2, the length of conveyor adjacent to a bay at any one time (belt increment) is equal to 1.5 seconds of conveyor travel so that during each belt increment only one lane in a bay may release an article. An order may be picked by dropping a large number of articles from a single lane in sequence. In this case, no other lanes could release since this one lane would fill the conveyor. In another case, all eight bays may drop an item in one time interval, which would then be followed by as many as seven belt increments with no other item dropped.

It is assumed that a general purpose data processing computer is used to maintain inventory of the articles in the storage area. This computer has been programmed so that it is aware of the configuration of the storage area, such as the number of groups of bays, the number of bays in each group, the number of lanes in a bay and the number of conveyor (belt) increments between the nearest bay and the exit detecting light beam. The desired order in which articles are to exit the storage area is fed into the computer and the computer generates the punches in the tape used to control the order picking system.

Drop synchronizing is controlled by a rotary cam switch, shown in FIGS. 2, 4 and 23, driven preferably by the conveyor drive. This rotary cam switch generates a pacer pulse whereby it defines the beginning of each conveyor increment, and 1.5 seconds interval, and generates synchronizing power pulses used to control the exact drop time within each 1.5 seconds interval, as shown in FIG. 4.

At the beginning of the tape, there will be blank shortage data sections in a number of the records because articles can be dropped but do not exit the storage area for that long until the first dropped article approaches the photocell detector. At the end of the tape, there will be blank drop data sections in a number of the records because dropping has stopped but articles

are still moving out of the storage area toward the photocell shortage detector.

As shown in FIG. 3, the tape, starting at the left end, has six frames of leader code to aid in visually identifying the start of a new order. This leader code is a control code as will hereinafter appear. This is followed by a rubout code and a "start of new order drop data" code which are control codes as shown in FIG. 3.

Then follows drop data. Each drop code consists of 10 two frames of code, a bay code and a lane code. There are two drop codes, bay 2, lane 7, bay 3, lane 6, followed by a single frame of leader code. A single frame of leader code is used between records.

Then follows another record (2nd) consisting of a 15 rubout code, a drop code, bay 0, lane 11, and a leader code.

Then follows another record (3rd) consisting of a 20 rubout code and a leader code. This record allows the conveyor to move one increment without dropping an article. This is necessary because the next scheduled drop is from bay 1, lane 5, but there is an article passing adjacent bay 1, the article that was dropped from bay 3, lane 6, so that no dropping should take place at this time.

Then follows another record (4th) consisting of a 25 rubout code, a "start of new order shortage data" code, a drop code (bay 1, lane 5), a shortage code and a leader code. The shortage starts here because by this time the leading dropped article is approaching the shortage detecting photocell shown in FIG. 2. It should be noted that articles will be dropped from bays 2 and 3 at the same time. During the next belt increment, an article will be dropped from bay 0 in the space in front of the bay 2 article. Then one increment will be 30 skipped, followed by dropping an article from bay 1 in the space behind the bay 3 article. Thus, the articles will appear in spaces A-D in the following order:

A — bay 0, lane 11

B — bay 2, lane 7

C — bay 3, lane 6

D — bay 1, lane 5

The bay 0 shortage data must come first because this article is leading.

40 Then follows the remaining three shortage data records, assuming that there are no more drop data codes.

As hereinafter more fully described, these records are read one at a time and recorded in the drop data shift registers in FIG. 17a-b and the shortage data printer shift registers in FIG. 22a-b. The manner of reading is one frame at a time. The tape reader advances in the forward direction to read one frame under the control of the functional programmer as it steps from step 2 to 3 to 0. In step FPS-2, the tape reader advances the tape one frame, in step FPS-3 the system waits for the tape reader to complete its motion, and in step FPS-0 the tape reader reads the frame of code. This cycle of the functional programmer is repeated for each frame of code in a record.

60 As shown in FIG. 4, the rotary cam switch produces four spaced drop control pulses and a pacer pulse during each conveyor increment. This rotary cam switch rotates one revolution per conveyor belt increment. The tape reader reads a complete record from the tape during the time that the drop control pulses are produced and registers this record in the drop data shift registers and/or shortage data shift registers. Then dur-

ing the time between the pacer pulse and the first drop control pulse, the logic circuit loads (or transfers) the drop data from the drop data shift registers to the multiplex (MPX) circuit to select a drop solenoid which is thereafter energized by the appropriate drop control pulse 1, 2, 3 or 4 as has been predetermined.

It was stated above that the remaining three records, 5th, 6th and 7th, on the punched paper tape in FIG. 3 contain shortage data if there are no more drop data codes. If there were no more drop data codes, the shortage data would follow the rubout code directly. There are no blank frames on the tape because a blank frame would be read as group 0, bay 0.

Actually, as shown in FIG. 3, these three records are assumed to contain drop data to aid in description of the purge operation hereinafter appearing. The 5th record contains a rubout code, a "start of new order drop data" code, two frames of next order drop data (DD), five frames of shortage data (SD), and a leader code.

The 6th record contains a rubout code, two frames of next order drop data code, five frames of shortage data code, and a leader code.

The 7th record similarly contains a rubout code, two frames of next order drop data code, the last shortage code of the present order (bay 1, frame 5, serial number), and a leader code. This 7th record is shown schematically since it is similar to the 6th record except for the bay and lane numbers.

GENERAL DESCRIPTION OF BLOCK DIAGRAM

Referring to FIGS. 1a-b, it will be seen that this block diagram shows the entire logic system that reads a punched tape and operates solenoids, shown at the right-hand side of FIG. 1b, to release articles from gravity lanes or chutes.

The figure numbers associated with the blocks in FIG. 1a-b indicate generally where each circuit is shown in the detailed drawings in FIGS. 7-26.

In this block diagram, there is shown a tape reader 2 that reads the punched paper tape one frame at a time. This tape reader 2 is provided with a tape reader enabling logic 4 that switches voltage to the tape reader contacts whenever reading is to be done, and switching this power off when it is not needed. This prevents unnecessary waste of power. The tape reader is also provided with a drive logic 6 that controls forward or reverse movement of the punched tape.

Console controls 8 in FIG. 1a include a selector switch that may be set to different modes of operation such as automatic wherein the tape reader controls dropping or purge operation wherein the remaining articles of an order are checked for shortage without starting dropping of the next order. This selector switch may also include a manual operation position wherein the drop data is put in from manual switches 8a rather than from the tape reader as generally shown in FIG. 1a. This console controls block also includes a long term power failure control relay contact for clearing all the set-reset memories to "0" when the system is restarted after power failure. This console controls block also includes a master reset switch for resetting the system and a run switch to indicate that the system is in a run condition as distinguished from test condition as hereinafter described in connection with FIG. 7.

This block diagram also has a control codes logic 10 that produces certain control signals as a result of the tape reader reading control codes. These control code

signals are used in operation of the system as hereinafter more fully described in connection with FIGS. 12, 13, 14 and 15.

This block diagram includes a purge logic 12 that is used to control completion of an order without starting the next order partially overlapping on the punched tape.

There is in FIG. 1a a set-reset memories logic 14 that holds certain signals until needed or canceled.

A photocell detector PC DET cancels a shortage condition set beforehand on a set-reset memory when an article exits.

The cam switch in FIG. 1a provides a pacer pulse and four drop control pulses each revolution. This cam switch rotates one revolution for each belt increment shown in FIG. 2.

There is provided a mode programmer control logic 16 for receiving certain combinations of signals and for setting mode programmer 18 in one of its ten steps in accordance therewith.

Similarly, there is provided a functional programmer control logic 20 for receiving certain combinations of signals and for setting functional programmer 22 in one of its steps 1-10, 13-18 in accordance therewith, steps 11-12 being reserved for other purposes.

A synchronizing pulse timing circuit 24 is provided in FIG. 1a for operation by the cam switch to provide SCR firing pulses for operating the drop solenoids at the lanes.

A clock 26 is provided for controlling the logic circuit system. This clock provides sequential A and B pulses for synchronizing the operation of the logic circuits to predetermined instants of time.

Drop data shift registers and logic 28 including a "drop data present" shift register 28a are provided for receiving the drop data codes from the tape reader and for holding them until they are used. The drop data present shift register is a control device for informing the logic system whether or not drop data has been read on each record.

A select bay logic circuit 30 and a select lane logic circuit 32 in FIG. 1b are provided for translating the binary octal codes coming from the drop data shift registers into select codes for operating the MPX.

An inhibit circuit 34 is provided for inhibiting transfer of select codes to the MPX in the event a too high numbered bay or lane is selected or if an unpaired bay or lane code has been read.

A multiplexor circuit 36 is provided for receiving the group, bay and lane codes and for operating the matrix circuit 38 to select a solenoid in lane solenoid circuit 40 for operation, which is thereafter energized by the drop pulse coming from synchronizing pulse timing circuit 24 in FIG. 1a.

In addition, there is a shortage printer 42 that prints an identification of an article that does not exit (interrupt the light beam to the photocell detector) when it is supposed to exit. This shortage printer receives the shortage data from shortage printer shift registers and logic circuit 44 which previously received it from the tape reader. These shortage data codes are directed to the several shift registers in circuit 44 by a binary counter that is stepped by the clock under the control of the mode and functional programmers.

A flow diagram for the mode programmer is shown in FIGS. 5a-b. This flow diagram contains ten rectangles number 0-9, respectively, to represent the ten

steps of the mode programmer. Within these rectangles are legends stating in a general way the functions that are performed in the respective steps of the mode programmer. For example, in step 0, the system can be reset to zero condition as indicated by RESET in the rectangle. The system can also be set to AUTO and RUN conditions. In addition, in this step MPS0, the system waits for the AUTO START signal.

To the left of these rectangles are a number of logic circuits comprised of AND and OR logics. These logics have input lines at their left sides and output lines at their right sides with the final output line going to the appropriate rectangle 0-9. These input lines have legends indicating in a general way what condition or combination of conditions is required to bring the mode programmer to that particular step. For example, to advance the mode programmer from step MPS0 to MPS1, a combination of four signals is required, namely MPS0, not purge complete, FPS0 and auto start. And there are other combinations of conditions also that will bring the mode programmer to step 1 from steps other than 0. The legend such as MP0-1 on a logic output line indicates that the associated combination of conditions will bring the mode programmer from step 0 to step 1.

To the right of these rectangles are a number of flow lines indicating the steps that are taken by the mode programmer during operation of the system. For example, the first line at the top leaving rectangle 0 is marked MP0-8. This means that this line indicates a shift of the mode programmer from step 0 directly to step 8. The remainder of this line is seen in FIG. 1b coming into rectangle 8.

A flow diagram for the functional programmer is shown in FIGS. 6a-c. This programmer has 17 steps 0-10, 13-18, with steps 11 and 12 reserved for manual or other control not illustrated in detail in FIGS. 17-26. This flow diagram is arranged similarly to the mode program flow diagram hereinbefore described so that its sequence and arrangement is apparent. The meanings of the various legends within the rectangles will become clear from the following detailed description of operation of the several modes of operation.

The logic circuit system shown in block diagram in FIG. 1a-b is shown in detail in FIGS. 7-26.

Referring to FIG. 7, there are shown the console controls, the reset logic, the purge logic circuit, the pacer control (CR) circuit, the tape reader out of tape control, and the shortage photocell control.

CONSOLE CONTROLS — FIG. 7

These console controls comprise a selector switch SS for selecting either automatic operation or purge operation. This selector switch actually has a third position for manual operation but the details thereof have not been shown as unnecessary for an understanding of the invention. The manual data input switches would be connected in parallel with the tape reader automatic input.

These console controls also include an auto start pushbutton PB circuit for providing a start control signal for automatic operation. The triangles 48 represent voltage input circuits that convert the higher voltage at the switch to a lower voltage suitable for operating the logic circuits, such as from 24 volts to 5 volts or the like.

These console controls also include a long term power failure control LTPFCR switch that opens on power failure and resets the set-reset memory circuits shown in FIGS. 7 and 16 as shown by the AND and OR logics A and 0 at the top of FIG. 7 when power is re-applied.

A master reset switch is included as an alternative way of performing the resetting at the top of FIG. 7.

A run switch, when closed, provides a control signal to allow generation of drop pulses.

PURGE LOGIC — FIG. 7

The purge logic circuit in FIG. 7 includes a purge execute set-reset memory 50 and a purge complete set-reset memory 52. The AND logics require a combination of a start of new order drop data control signal NODDC, functional program step 9 signal FPS9, and a purge signal to set memory 50 into purge execute. This allows the purge operation to proceed, as herein-after described.

When all the dropped articles have been purged (checked for shortage), the AND logics require a combination of a purge execute signal, mode program step MPS3 signal and a start of new order shortage data control signal NOSDC to set memory 52 to the purge complete state. This causes resetting of memory 50 to not purge execute NPEX state. Memory 52 is reset upon reversal of the tape reader by the combination of functional program step FPS9 and start of new order drop data code NODDC signals, as hereinafter described along with the description of operation.

PACER CONTROL — FIG. 7

The pacer control circuit in FIG. 7 comprises a cam switch CSW that closes once during each conveyor belt increment of movement. A timer 54 times dropout of any codes that may be in the MPX in preparation for registering a new drop code therein. For this purpose, the combination of a NAND logic N, an AND logic A and another NAND logic N along with timer 54 first cause a high signal to be applied to sink power output S for a timed interval and then timer 54 re-applies the low HOLD signal to maintain the MPX relays energized following selection of the bay and lane.

In the PACER pulse circuit, a timer 56 and NAND and AND logics first allow the pacer pulse to pass. The timer then times out to limit the length of the pacer pulse.

A tape reader contact TR closes when the tape reader is out of tape to provide a TROOT signal (tape reader out of tape).

A "shortage" photocell contact closes when an exiting article interrupts the light beam in FIG. 2 to cancel the shortage data so that it won't be printed.

The AND, OR and NAND logics function as follows:

And Logic

The AND logics indicated by A in FIG. 7 perform the AND-operation when both inputs have a low. The output is low. If either or both inputs have a high, the output is high. The circles at the inputs and/or outputs indicate that low is significant in the operation.

Or Logic

The OR logics indicated by 0 in FIG. 7 perform the OR-operation when either input is low or both. The output is low. If both inputs have a high, the output is high.

Nand Logic

The NAND logics indicated by N in FIG. 7 perform the NAND-operation (inversion), that is, generate a low output signal if and only if both inputs are high. If either input is low, the output will be high.

The AND, OR and NAND logics in the remainder of the figures are identified by their characteristic symbols similar to those in FIG. 7 and operate in a similar manner.

MODE PROGRAMMER — FIG. 8

The mode programmer MP shown in FIG. 8 has ten inputs MPSET0-9 and ten outputs MPS0-9 and is equivalent to ten set-reset memories except that one and only one of the group of ten can be in the "1" state at a time. Thus, when one output is set to 1, all the others are set to "0." This mode programmer also has a sync-1 pulse output to signal the clock to start whenever there is a "set" input signal applied to the mode programmer. Both the sync-1 and clock-B signals are then applied to the set input at the lower portion of the mode programmer to set it to the new 1 output according to the MPSET0-9 input that is present. The AND, OR and NAND input logics at the left-hand side of FIG. 8 determine the combinations of conditions required to set the mode programmer into any output state. The meanings of the legends thereat will become clear from the following description of operation. The mode programmer steps to any output when a set signal is applied to the corresponding input. This set signal causes a sync-1 output signal that is applied to run the clock. The sync-1 signal and the clock B signals together cause the mode programmer to be MPSET0-9 to 1 state at the output corresponding to the set input and all other outputs are set to 0 state.

FUNCTIONAL PROGRAMMER — FIGS. 9a-b

The functional programmer FP shown in FIGS. 9a-b is generally similar in structure to the mode programmer except that it has 17 outputs 0-10 and 13-18 instead of 10, outputs 11 and 12 being shown unused because they are for the manual operation not shown in detail. Therefore, it uses a units section and a tens section. All ten outputs FPUS0-9 of the units section are used but only the first two outputs FPTS0-1 of the tens section are required because the number of outputs does not go into the 20's.

Like the mode programmer, this functional programmer also has AND, OR and NAND input logics at the left-hand side of FIGS. 9a-b that determine the combinations of system states required to set the functional programmer into each output state. The meanings of the legends at the inputs to these logics will become clear from the following description of operation.

The functional programmer additionally has a group of translation logics down the middle of FIGS. 9a-b that translate the set signals FPSET0-10, 13-18 into ten units and two tens signals FPSETU0-9 and FPSETT0-1 usable by the units and tens programmer units.

This functional programmer additionally has a column of translation logics down the right side of FIGS. 9a-b that translate the units and tens outputs FPUS0-9 and FPTS0-1 into functional programmer output signals FPS0-10, 13-18. The translation logic for output signal FPS1 is shown at the upper left-hand portion of FIG. 8 since it performs a double duty.

The functional programmer operates like the mode programmer. Each time an input signal is applied, it

generates sync-2U and sync-2T signals. These two signals are applied to the AND logic at the upper right-hand portion of FIG. 9a and the sync-2 output thereof is applied to run the clock to provide the aforementioned CLK A and CLK B signals. The sync-2U and CLK B signals are applied through an AND logic in FIG. 9b to set the units programmer section to the new state. The sync-2T and CLK B signals are applied similarly through an AND logic in FIG. 9b to set the tens programmer section to the new state.

CLOCK — FIG. 10

The clock shown in FIG. 10 performs several functions. The upper portion thereof generates timing signals for operation of all sequential integrated static logics such as the mode programmer, functional programmer, binary counter, drop data input shift registers, and printer shift registers and printer buffer shift registers. These timing signals consist of a first pulse from the CLK A output followed by a time-spaced second pulse from the CLK B output. These timing signals are produced in response to an input signal at the sync-1 or sync-2 input terminal.

The clock includes at the middle thereof, set off by broken lines, a logic for detecting undervoltage conditions, or short dips in the power supply voltage that might change the setting of logic memories. Under such condition a 1 state would appear at the UV and UVSET outputs to set the functional programmer to step FPS1 and the mode programmer to step MPS0. This stops the system and must be manually restarted.

The clock also includes a reset logic at the lower portion thereof. When power is applied to the system, "initial application of power" output INIP0 goes to 1 state. This signal is applied to FIG. 23 to inhibit drop pulses during the disturbance caused by application of power.

An alternative inhibit signal to the OR logic in FIG. 23 is obtained from the UV output of the clock to prevent drop pulses as a result of undervoltage conditions.

TAPE READER — FIG. 11

The tape reader has eight contacts that close when they sense respective punched holes in the tape. Thus, the tape reader contacts translate each frame of code on the tape into signals at outputs T1-T8.

The tape reader has an input switching logic circuit at the upper left-hand portion of FIG. 11 that switches voltage to the tape reader contacts when codes are to be read to avoid application of power to the contacts at all times. This logic circuit determines the combinations of conditions required to energize the tape reader contacts. According to the first combination of conditions, the mode programmer must not be in step MPS0 or step MPS6, the functional programmer must be in step FPS0, and the tape reader must not be out of tape. TROOT means tape reader out of tape. This is for reading control codes. The second combination of conditions requires that the mode programmer be in step MPS4 and that the functional programmer must be in either step FPS7 or step FPS8. This is for reading drop data. The third condition requires that the mode programmer be in step MPS5. This is for reading shortage data.

At the lower portion of FIG. 11 is shown the tape drive logic for controlling forward and reverse movements of the tape, forward under normal reading and reverse when the tape must back up to the start of the

new order after a purge operation when shortages at the end of the previous order were checked, and arti- cles on the next order were not dropped.

This drive logic comprises a timer 58 that times tape advance of one frame. As will be apparent, in functional program step FPS2 and AND and NAND logics initiate operation of forward winding FOR through source power output 6C24. Timer 58 upon timing out terminates such forward operation and also provides a read tape timer signal RPTM that steps the functional programmer to step FPS3. This drive logic also has provision for causing operation of reverse winding REV through source power output 5C24 when the mode programmer is in either step MPS8 or MPS9. This is the back-up after purge operation when reading of the new order drop data is desired.

It may be noted at this time that source power outputs 4C24, 5C24 and 6C24 have an inhibiting circuit in FIG. 19 where reading is inhibited in response to a PURGE EXC or a DE signal. During purge execute only shortage is checked so that reading is inhibited, this signal coming from FIG. 7. The DE signal comes from FIG. 20, sh. 10, and indicates too high numbered bay or lane or unpaired bay or lane.

CONTROL CHARACTER AND DROP DATA LOGIC — FIG. 12

This logic shown on sh. 8 at its upper part senses the code T5, T6, T7 and T8 and provides a control character signal CC in response thereto. As shown in FIG. 3, this code appears as the leader code, a portion of the rubout code, a portion of the start of new order drop data code, and a portion of the start of new order shortage data code. The lower portion of the logic senses the code T7, T8 and T5 or T6 or neither, but not both, and provides a drop data signal DD in response thereto. These two signals CC and DD are used in various places as will hereinafter appear from the description of operation of the system.

SHORTAGE DATA LOGIC — FIG. 13

This logic senses codes which are neither CC codes nor DD codes and are therefore assumed to be shortage data codes SD. This shortage data signal SD is used in various places as will hereinafter appear from the description of operation of the system.

RUBOUT CODE LOGIC — FIG. 14

This logic shown on sh. 14 senses a code having all eight punches, T5-T8 by the control character CC signal and T1, T2, T3 and T4 by the parallel AND logics, and provides a RUBOUT signal in response thereto. This signal is inverted to provide also a NRUBOUT, not rubout, signal. These signals are used in various places as will hereinafter appear from the description of operation of the system.

NEW ORDER DROP DATA, LEADER AND NEW ORDER SHORTAGE DATA CODES LOGIC — FIG. 15

The upper part of this logic shown on sh. 13 senses a new order drop data code. This code is shown on the tape in FIG. 3 as a "start of new order drop data" code and consists of punched holes in bit positions T1, T5, T6, T7 and T8 and no holes in bit positions T2, T3 and T4. As will be apparent, the inversion of the T2, T3 and T4 inputs requires that these three bits not be present.

And the sum of T1 and CC requires that T1 and T5, T6, T7, T8 be present, CC being the equivalent of the latter four bits as described above in connection with the control character logic. These inputs provide a new order drop data code signal NODDC that is inverted to provide also a not new order drop data signal NNODDC. These signals are used in various parts of the system as will appear in the description of operation hereinafter.

10 The middle part of this logic senses a leader code shown on the tape in FIG. 3 as T5, T6, T7, T8 present and T1, T2, T3, T4 not present. For this purpose, the inversion of the T1, T2, T3, T4 inputs requires that these not be present. The control character signal CC input requires that T5, T6, T7, T8 be present. These inputs provide a LEADER output signal that is inverted to provide a not leader output signal NLEADER also. These signals are used in various parts of the system as hereinafter described in connection with the description of operation thereof. In this connection, it may be noted that the T2, T3 and T4 inverted inputs are the same as were used above for the NODDC signal.

15 The lower part of this logic senses a new order shortage data code shown on the tape in FIG. 3 as a "start of new order shortage data" code, consisting of T2, T5, T6, T7, T8 present and T1, T3, T4 not present. For this purpose, the inversion of T1, T3, T4 inputs (T3, T4 being the same inputs as used above) requires that these not be present. The sum of T2 and control character signal CC inputs requires that T2, T5, T6, T7, T8 be present. These inputs signals provide a new order shortage data code output signal NOSDC that is used in various parts of the system as will become apparent in the description of operation.

SET-RESET MEMORIES — FIG. 16

20 These logics are similar to flip-flops and are set directly to 1 or 0 state as required without clocking. A 1 signal at the upper left-hand input changes the set-reset memory to its 1 state, providing a 1 signal at the corresponding upper right-hand output. Alternately, a 1 signal at the lower left-hand input changes the set-reset memory to its 0 state, providing an 0 signal at the upper right-hand output. Whenever the upper right-hand output is in a 1 state, the lower right-hand output is in an 0 state, and vice versa.

25 Referring to FIG. 16, there are five set-reset memories, the third one having two units in tandem. These set-reset memories are identified by their output reference characters. Thus, the first one at the top is a drop data set-reset DDSR1, the suffix 1 indicating its 1 state, and the suffix 0 at the lower output indicating its 0 state. The second one is a print enable set reset PRENB. The third one is a shortage set-reset as indicated by the shortage and not shortage outputs. The fourth one is a print reset PRST set-reset memory. And the fifth one is an auto run set-reset memory. The reference characters at the inputs, including the OR logic at the lower left-hand input of the first (upper) one and the AND logic at the upper left-hand input of the fourth one, indicate the conditions, combination or alternative conditions required to operate these set-reset memories. These conditions will become apparent from the following description of operation of the system.

**DROP DATA SHIFT REGISTERS AND LOGIC —
FIG. 17a-b, sh. 13.**

There are twelve shift registers for registering drop data read from the punched paper tape and a control shift register. The upper six shift registers receive the bay code and the next six shift registers receive the lane code. The thirteenth shift register is a drop data present shift register and registers an indication that drop data is present.

Of the first six shift registers, the upper three are group shift registers GSR4-6 that receive the three bit binary octal code indicating the group of bays. The next three are bay shift registers BSR1-3 that receive the three bit binary octal bay code.

The next six shift registers are lane shift registers LSR1-6 that receive the binary octal tens (LSR4-6) and binary octal units (LSR1-3) codes.

Each of these shift registers is an eight bit logic, receives drop data in the serial shift SS mode at inputs T1, T2, etc., and is reset to zero in the parallel gating PG mode. Each of the serial shift and parallel gating are under the control of clock A and B timing pulses.

The logics at the left-hand side of the shift registers control both resetting of the shift registers to zero condition and shifting of the drop data thereto under control of the mode programmer and functional programmer and the aforementioned clock pulses. These shift registers are internally paired as indicated by the broken lines so that only one serial shift SS input and only one parallel gating PG input is required for each pair.

The logics at the right-hand side of the shift registers are gating devices that gate the drop data from the outputs of the shift registers into the matrix MPX under the control of automatic data shift into MPX control signal ADIE1.

At the lower portion of FIG. 17b, the logics at the output of the drop data present shift register DPSR provide a drop data in output position signal DIOP and an inversion thereof DNIOP meaning data not in output position. These logics also provide a drop data present signal DDPRS, and a signal TEDR indicating that drop data is present but is not in the output position of the shift registers, consequently requiring shifting to output position before the MPX can be set.

SELECT BAY LOGIC — FIG. 18

This logic shown on sh. 17 at its upper portion receives the group code from FIG. 17a, which is a three bit, binary octal code, at its inputs AB4, AB5, AB6 having the binary bit values 1, 2 and 4, respectively, and provides a select multiplexor signal at one of five outputs SM0-4 to select a respective source power output SPO0-4, three being shown each of which is associated with a respective multiplexor MPX0-4, one being shown in FIG. 24. For this purpose, a zero input provides a signal at output SM0, a binary 1 on input AB4 provides a signal on output SM1, etc. This group code selects the source power output jointly with gating signal ADIE1 that is present when codes are gated out of the drop data shift registers, FIGS. 17a and 21, 21, sh. 15 and 17.

This logic at its lower portion receives the bay code, which is a three bit, binary octal code, at its input AB1, AB2, AB3, having the binary bit values 1, 2 and 4, respectively, and provides a bay select signal at one of

eight outputs SEL. 0-7 to select a respective bay in the concurrently selected group of eight bays. For this purpose, a zero input provides a signal at output SEL. 0, a binary 1 on input AB1 provides a signal on output SEL. 1, etc. The multiples at the left-hand side of source power output SPO0 indicate similar connections to each of the other four source power outputs SPO1-4.

SELECT LANE — FIG. 19

10 This logic shown on sh. 16 at its left-hand side receives the lane code from the drop data shift registers, which is a three bit, binary octal tens and units code, having the binary bit values 1, 2, 4 at tens inputs AL4, AL5, AL6, respectively, and having the binary bit values 1, 2, 4 at units inputs AL1, AL2, AHL, respectively. This logic provides pick lane signals at two or three of the ten outputs PICK1-10 to pick one of the forty lanes in the selected bay. For this purpose, two output signals are required for coordinate selection

tional program step FPS14 except during the time when data is actually being shifted in the shift registers by the CLK B pulse.

SHORTAGE PRINTER, BINARY COUNTER AND PRINTER SHIFT REGISTERS — FIG. 22a-b

There are five printer shift registers PSR1-5 that are parallel gated (PG) to receive the five frames of shortage data, including bay and lane codes and serial number (three frames) as shown on the tape in FIG. 3.

The binary counter and the logics at the left-hand side of the printer shift registers distribute the five frames of shortage data to these shift registers in the following order. BC-0, BC-1, etc. indicate the output bits of the binary counter.

- BC-0 1st frame into PSR5
- BC-1 2nd frame into PSR2 and 1st frame from PSR5 to PSR1
- BC-2 3rd frame into PSR5
- BC-3 4th frame into PSR4 and 3rd frame into PSR5 to PSR3
- BC-4 5th frame into PSR5

As will be apparent, shortage data is parallel gated into the shift registers on functional program step FPS4 and the binary counter is advanced in step FPS5, the mode programmer being in step MPS5. The clock A and B pulses time both the parallel gating of the shortage data and stepping of the shift register.

The T4 and T8 inputs to the logics at the upper left-hand part of FIG. 22a are for special codes T8 and T4, T8. The T8 code is used when spaces on the conveyor are purposely inserted. The space on the conveyor is left empty by the absence of a drop code on that particular tape record. The T8 code provides a shortage data inhibit print SDIP signal that is inverted by the logic at the top of FIG. 22a to prevent energization of the printer coil, thereby to prevent printing of any shortage when the empty space passes the light beam article detector.

The T4, T8 code prevents printing as just described and also advances the printer tape one space. For this purpose, the T4, T8 code energizes the printer tape drive during functional program step FPS16 to advance the tape.

The logic at the top of FIG. 22a also parallel gates (PG) any shortage data that may be in the printer shift registers PSR1-5 into the printer buffer shift registers on mode program step MPS5 in order to get the proper shift in timing at the shortage detection point. The SDIP and NSDIP signals are also used in the functional programmer input logics in FIG. 9b.

SYNCHRONIZING PULSE TIMING LOGIC — FIG. 23

This logic is for the purpose of generating drop pulses P1, P2, P3 and P4 shown graphically in FIG. 4 and for timing the length thereof. As shown in FIG. 23, sh. 20, the cam switch has four contacts CSW1-4 that are momentarily closed in sequence once per belt increment shown in FIG. 2. As hereinbefore mentioned, the fifth contact CSW of this cam switch shown in FIG. 7 generates a pacer pulse shown in FIG. 4 that controls transfer of drop data into the MPX. This pacer pulse occurs when a pusher P is under the light beam as shown in FIG. 2.

One of these contacts CSW1-4 operates a power output circuit that in turn operates a silicon controlled rec-

tifier (SCR) pulse circuit to provide a corresponding power pulse P1, P2, P3 or P4 for energizing the lane solenoid that has been previously selected thereby to drop an article from that lane onto the conveyor belt in the proper space between two pushers.

At the left-hand portion of FIG. 23 is shown an inhibit OR-AND logic circuit whereby either an initial power-on signal INIPO or an undervoltage signal UV inhibits the generation of drop pulses as a result of such disturbance.

At the lower portion of FIG. 23 is shown a logic circuit for timing the length of the drop pulses. Any one of the four cam switch contact closures along with the run signal causes the power output to be gated on, provided an inhibit signal is not present, and also causes starting of timer 64. The timer times the length of time that the SCR circuit is maintained energized and thus times the length of the drop pulse. When timer 64 times out, it terminates the gating of the power output circuit so that the drop pulse ends at the end of the A.C. half-cycle when the SCR voltage decreases to zero.

MULTIPLEXOR MPXO — FIG. 24

This is the circuit of one multiplexor MPXO. For the total system, there will be five multiplexors like this, MPXO-4, one for each group of bays 0-4.

This circuit has eight relay circuits, one for each bay in the group. One of these relay circuits is shown in detail, the circuit for bay 0, and the other seven circuits are represented by vertical lines SEL. 1-7 since they are similar.

The bay in the selected group of bays MPXO is selected by applying a signal to one of the inputs SEL. 0-7 at the lower portion of FIG. 24. This signal comes from FIG. 18. This results in selection of one of the vertical columns of relays like that shown.

The bay having been so selected, one of the 40 lanes in this bay is then selected by applying signals to two or three of the inputs PICK1-10 at the left-hand side of FIG. 24 as hereinafter more fully described. For example, a lane code of 4 in FIG. 19, that is, a 1 bit on input AHL and 0 bits on the other inputs, provides signals on outputs PICK1, 6 and 7. This causes energization of relays MA, MHL and M1 in FIG. 24. Following the description of FIGS. 25 and 26, it will be shown how these relays energize the lane 4 solenoid in FIG. 26.

BAY 0 MATRIX — FIG. 25

This circuit is a matrix or coordinate arrangement of 50 lane select relays. There is one circuit like this for each bay and it is capable of selecting any one of the 40 lane solenoids for energization by the drop pulse.

As shown in FIG. 25, this coordinate selection relay circuit is divided by a broken line down the middle into two groups, GRP1 and GRP2, the ten relays in each group being capable of selecting any one of the twenty lanes with the aid of the high-low (section select) relay HL. Since the ten GRP2 relays are similar to the ten GRP1 relays, they have been shown schematically as a rectangle.

It will be apparent that whereas the relays in FIG. 24 have first contacts in their respective hold coil circuits, for example, contact MA1 of relay MA, these relays have second contacts in the matrix circuit of FIG. 25, for example, contact MA2, etc. Thus, it will be apparent that relays MA, MB, MC, MD and ME of FIG. 24 select the five horizontal lines in FIG. 25, respectively.

At the same time, relays M1-4 of FIG. 24 select the four vertical lines in FIG. 25, respectively, relays M1 and M2 selecting either line in GRP1 and relays M3 and M4 selecting either line in GRP2.

Relay HL in FIG. 25 is a section select relay and functions to select either the A or B section in the selected group.

Continuing with the lane 4 selection that was started in connection with FIG. 24, it will be recalled that relays MA, MHL and M1 were energized. This causes energization of relays 1R1 and HL in FIG. 25. How this selects a lane will be described in connection with FIG. 26.

BAY 0 RELEASE SOLENOIDS — FIG. 26

As shown in FIG. 26, each bay has 40 solenoids, one for each lane. These solenoids are divided into two groups, GRP1 and GRP2, as indicated by the broken line. Each group is further divided into two sections, the first group having sections S1A and S1B and the second group having sections S2A and S2B. Each section has ten solenoids, the solenoids in section S1A being shown in detail and the other three sections being shown schematically as rectangles since they are similar. The lane numbers, however, are shown in these three rectangles to show which solenoids appear in each section.

As will be apparent, the ten GRP1 relays 1R1-1R10 in FIG. 25 select solenoids in both sections S1A and S1B of the first solenoids group, respectively, in the same order. Similarly, the ten GRP2 relays 2R1-2R10 in FIG. 25 select solenoids in both sections S2A and S2B of the second solenoids group, respectively, in the same order.

Completing now the description of selection of lane 4 that was started in connection with FIG. 24, it will be recalled that relays 1R1 and HL in FIG. 25 were energized. As a result, these relays close contacts 1R11 and HL2 and open contact HL1 to close a circuit from common conductor PCOM through solenoid L4 to drop pulse conductors P1-4. This constitutes selection of the lane 4 solenoid that will then be energized at the proper time by a drop pulse to drop an article from lane 4 of bay 0 onto the conveyor.

OPERATION

When power is initially applied to the system, the clock in FIG. 10, sh. 13 sends out an initial power on signal INIPO that performs two functions:

1. It resets or clears all of the set-reset memories to 0 condition; and
2. It inhibits the firing circuits of the SCR's that control the article release solenoids.

As will be apparent, the set-reset memories must initially be in a 0 condition from which they can then be operated as hereinafter described. Also, any disturbance caused by application of electrical power to the system should not be allowed to fire any SCR's as that would cause inadvertent dropping of an article from a lane.

Let it be assumed that both the mode programmer and the functional programmer are initially in their 0 condition. They can be set in this condition by pressing a master reset button, which would also clear all the set-reset memories to their 0 condition and reset the tape reader input shift registers to their 0 condition.

The mode programmer is a ten step programmer having ten signal inputs 0 to 9 and one clock input and ten signal outputs 0 to 9 and one sync output. When a 1 signal is applied to an input, the mode programmer provides a sync output that is applied to the clock. This sync causes the clock to provide A and B clock pulses in time spaced sequences. The B pulse is applied to the clock input of the mode programmer, causing it to provide a 1 output at the output terminal corresponding to the 1 input. Each output 1 is directly set by an input 1 and there can be only one output at any time. Thus, when another input signal causes a corresponding output on another output terminal, all the other outputs go to 0.

The functional programmer is an 18 step programmer consisting of a units section similar to the mode programmer and a tens section. The units section has ten inputs 0 to 9 and a clock input, ten outputs 0 to 9 and a sync output like the mode programmer. However, in the tens section, only the first two inputs 0 and 1 and the clock input, the first two outputs 0 and 1 and the sync output are used since the required steps are limited to 18. The functional programmer operates in a manner similar to the mode programmer in that an input signal produces a corresponding output through the aid of sync and clock pulses and there can be only one output at any time. For any output above 9, there will of course be an output from both the units and tens sections.

It will be recalled that the mode programmer and functional programmer were assumed to be in their 0 condition with a 1 bit at the 0 output. This condition may be indicated as step 1 of the drop program:

DP-1 MPS-0 FPS-0

meaning mode program step 0 and functional program step 0 in the first step of the drop program. In this DP-1 step, the system waits for auto start as depicted in FIG. 5a.

To initiate automatic operation of the system, the operator presses an auto start button in the console, FIG. 7, sh. 9. This causes the following functions to be performed:

3. The undervoltage-sensing flip-flop in the clock (FIG. 10, sh. 13) is reset to 0 condition;
4. The mode programmer is set from 0 to 1.

The conditions requisite to setting the mode programmer from 0 to 1 are shown on the flow diagram as:

Not purge complete means that the system is not in the purge mode of operation. The second step of the drop program may be indicated as:

DP-2 MPS-1 FPS-0

In this step the following functions are performed:

5. A set-reset memory (FIG. 16, sh. 13) is set to its "shortage" indicating condition;
6. A set-reset memory (FIG. 16) is set to its "auto run" indicating condition;
7. The tape reader input shift registers (FIGS. 17a-b, sh. 15) are reset to 0 condition;

DP-10 MPS-3 FPS-9

The following function is performed:

24. Go to FPS-2.

As will later become apparent, FPS-9 has a purpose in 5 the purge mode of operation. The next step of the drop program may be shown as:

DP-11 MPS-3 FPS-2

In this step, the following functions are performed:

25. Advance tape reader to read the bay 2 drop code.
26. Set functional programmer from FPS 2 to 3.

The tape reader advances the tape and the functional programmer steps from FPS-2 to 3 to 0 to read the bay 15 2 drop code in the manner hereinbefore described with other readings. This causes the mode programmer to go to step 4, with the following requisite conditions:

MPS-3		MPS 3-4
FPS-0		
DD		

DD means that there is a drop data signal present as herein-before described in connection with FIG. 12. This step 4 of the mode programmer is for indicating tape load error trouble condition in the event a purge complete signal is present and need not be considered here. This step may be shown as:

DP-12 MPS-4 FPS-0

This causes the functional programmer to be set to step 6 under the requisite conditions:

MPS-4		FPS 0-6
FPS-0		

This step is shown as:

DP-13 MPS-4 FPS-6

In this step, the following functions are performed:

27. A decision is made whether to go to FPS-7 or 8 40 depending upon the setting of the drop data set-reset memory. Since this is the first time through, the drop data S-R memory will be in the 0 state; consequently, the stepping will be from FPS 6-7.
28. Set FPS from 6 to 7.

This step is shown as:

DP-14 MPS-4 FPS-7

In this step, the following functions are performed:

29. Voltage is reapplied to the tape reader contacts in FIG. 11, such voltage having been interrupted when the functional programmer left step 0 and was set to step 6. This switching of voltage on the tape reader contacts conserves power.
30. Load bay 2 code into the tape reader input shift 55 registers in FIG. 17a.
31. Set the drop data set-reset memory to bit 1.
32. Set the functional programmer to step 2 to advance the tape.

This step may be shown as:

DP-15 MPS-4 FPS-2

The functional programmer then advances the tape and steps from FPS-2 to 3 to 0 to read the lane 7 code frame, and advances as follows:

MPS-4		FPS 0-6

3,777,910
22

FPS-0)

This will be recognized as the same as step DP-12 above. Since the drop data set-reset memory in FIG. 16 is now in setting 1, the functional programmer will go to step FPS-8 as follows:

FPS-6		FPS 6-8
DDS-R = 1		

10 This step may be shown as:

DP-16 MPS-4 FPS-8

In this step, the following functions are performed:

33. Voltage is reapplied to the tape reader contacts.
34. Put lane 7 drop code into the tape reader input shift registers in FIGS. 17a-b.
35. Set the drop data set-reset memory (DD S-R) to 0 bit in FIG. 16.
36. Put a setting into the "drop data present" indicating shift register in FIG. 17b.
37. Step the functional programmer to step 2 to advance the tape for reading the bay 3 drop code.

From the foregoing, it will be recalled that the bay 2 25 drop code was read and put into the input shift registers in FPS-7. Thereafter, the lane 7 drop code was read and put into the input shift registers in FPS-8. The bay code is gated into the first six input shift registers in FIG. 17a by the FPS-7 gating signal. Similarly, the lane 30 code is gated into the next six input shift registers in FIG. 17a-b by the FPS-8 gating signal. In addition, the FPS-8 signal puts a bit into the last input shift register in FIG. 17b to indicate that drop data is present, thus providing a DDPRS (drop data present) signal for purposes hereinafter described.

In a similar manner, the functional programmer cycles through settings 8 to 2 to 3 to 0 to read another frame, bay 3 drop code this time, and cycles from setting 0 to 6 to 7 to put this bay 3 code into the first six shift registers, etc., reading lane 6 drop code thereafter and registering it.

The functional programmer then goes to step 2 and 45 3 and 0 to advance the tape to read the leader code in step FPS-0. This step may be shown as:

DP-17 MPS-4 FPS-0

With the leader code having been read, the mode programmer goes to step 6 under the following conditions:

FPS-0		MPS 4-6
MPS-4		
Leader		

as shown on the flow chart in FIG. 5a. In this step, the following functions are performed:

38. Advance drop data to output position.
39. Go to MPS-7.

Since the input shift registers are 8 position registers and the two pairs of drop codes are in the first 4 positions, pulses will be generated in MPS-6 to advance the drop data 4 places to output position under the following 60 requisite conditions:

MPS-6		MPS 6-6
DDPRS		
DNIOP		

DDPRS means drop data present and DNIOP means data not in output position. Each time an MPSET 65 6

pulse is generated in FIG. 8, the MPS-6 signal shifts the data in the "drop data present" shift register in FIG. 17b until data appears at the output, causing the DNIOP signal to terminate and the DIOP (data in output position) to appear. This causes the mode programmer to be set as follows:

MPS-6	}	MPS 6-7
DIOP	}	

to step 7. We now are in the following drop program step:

DP-18 MPS-7 FPS-0

These conditions cause setting of the functional programmer to step 10 as follows:

FPS-0	}	FPS 0-10
MPS7	}	

We now are in the following drop program step:

DP-19 MPS-7 FPS-10

In this step, the following functions are performed:

40. Set a "shortage" set-reset memory to sense whether a package is exiting.

41. Wait for pacer pulse.

If a package exits at the photocell, the shortage set-reset memory in FIG. 16, sh. 13 will be reset, thus canceling the shortage indication.

Since there is drop data registered, the functional programmer advances to step 13 as follows:

FPS-10	}	FPS 10-13
Pacer	}	
DIOP	}	

The system is now in the following drop program step:

DP-20 MPS-7 FPS-13

In this step, the following functions are performed:

42. Serial shift of drop data present (DDPRS) shift register.

43. Start to set MPX.

44. Go to FPS-14

In function 42, the bit corresponding to the drop data now to be transferred to the MPX is first shifted out of the DDPRS shift register. In function 43, an AND logic at the right-hand side of FIG. 21, sh. 17 is gated so that the drop data can be transferred to the MPX in step FPS-14 upon the occurrence of the clock B pulse. The system is now in the following drop program step:

DP-21 MPS-7 FPS-14

In this step, the following functions are performed:

45. The drop data (bay 2, lane 7) in output position is gated from the input shift registers in FIGS. 17a-b into the multiplexor (MPX) in FIG. 24 and matrix (MTX) in FIG. 25 to select group MPXO of bays from groups MPXO-4, to select bay 2 from bays 0-7 in that group at the lower portion of FIG. 18 and FIG. 24, and to select lane 7 from lanes 0-47 in that bay.

46. Apply hold signal to MPXO.

47. Serial shift of input shift registers.

48. Go back to FPS-13 if there is more drop data.

The drop data (bay 2, lane 7) is gated to the MPX and MTX under the following conditions by the logic in FIG. 21.

5	Auto run	}	ADIE1
	Clk B		
	FPS-14		

Translating logic converts the octal codes (bay 2, lane 7) to selections of group 0 of bays, bay 2 in group 0,

10 and lane 7 in bay 2 of group 0. The manner in which the translating logic does this will be readily apparent when the octal codes shown on the tape are put into this logic. For example, any bay code from 0 to 7 will select group MPXO and the desired bay (2) in that group. Any bay code from 10 to 17 will select group MPX1 and the desired bay in that group. Any bay code from 20 to 27 will select group MPX2 and the desired bay in that group, etc., up through groups MPX3 and MPX4.

15 20 In a similar manner, any octal lane code from 0 to 47 (0-7, 10-17, 20-27, 30-37, 40-47) will be translated into a "pick" code that will operate the matrix (coordinate) circuit. This circuit has five horizontal selections, pick 1-5, and four vertical selections, pick 7-10, giving a possible 20 selections and high and low that doubles it to a possible 40 selections of lanes. For example, to select lane 7, the octal code is translated to pick 1, pick 6 and pick 10 to operate relay 2R6 in group 2 and relay 30 HL. This causes selection of solenoid L7 corresponding to lane 7.

35 The drop solenoid for lane 7 of bay 2 has now been selected but it will not be actually energized until a drop pulse shown in the graph in FIG. 4 is applied thereto through one of the conductors marked P1-4 and PCOM. Four drop pulses Nos. 1, 2, 3 and 4 along with the pacer pulse are generated by a rotating cam switch driven by the conveyor. These pulses are generated in the order shown in FIG. 4.

40 45 The arrangement is such that the pacer pulse is generated when a pusher P on the conveyor is under the photocell detector as shown in FIG. 2. As shown in FIG. 4, the drop data is transferred, or loaded, from the tape reader input shift registers into the multiplex and matrix during the time between the pacer pulse and the first drop pulse. The next complete record on the tape is then read and registered during the time that the four drop pulses occur.

50 55 Four time spaced drop pulses are provided so that the appropriate pulse can be used on each lane depending upon the position of the lane with respect to the space on the conveyor, the space between two pushers, into which the article is to be dropped. For example, if the lane from which an article is to be dropped is at the upstream side of the bay, the first drop pulse should be used to insure that the article will drop in front of the pusher. On the other hand, if the lane is toward the downstream side of the bay therefrom, the second, third or fourth pulse may be used depending upon the size of the article, width, etc.

60 65 It was heretofore described how the first drop code, bay 2, lane 7, was put from the input shift registers into the multiplex and matrix. It will be recalled that the input shift register contains a second drop code, bay 3, lane 6. When the first drop code is used from the shift registers, it is necessary to shift the next drop code into the output positions on the input shift registers.

The aforementioned function 46 hold signal is applied in response to the pacer pulse in FIG. 7. As shown therein, closure of the pacer contacts CSW of the rotary cam switch causes the logic to apply a 0 bit to the sink power output S to terminate the hold signal for the duration of timer 54 of about one second. This allows any codes in the MPX and MTX to drop out. At the end of this time interval, the output of the timer goes to 1 that is inverted to an 0 by the NOT logic and applied to the AND logic to reapply the hold signal. Thus, the drop code is held in the MPX until the drop pulse comes along to drop the article.

Since the first drop code has now been transferred to the MPX and MTX, the next drop code must be shifted to the output positions so that it can then be used in the same way to select another drop solenoid. This is done also in FPS-14 as indicated above by applying a serial shift pulse to the input shift registers. As a result, bay 3, lane 6 code is now in the output position.

Since there is more drop data, the following drop program step occurs:

FPS-14	)		FPS 14-13
DIOP	)		

As indicated, the functional programmer recycles through step 13 to 14 to transfer the second drop code into the MPX and MTX (multiplex and matrix) and select solenoid L6 corresponding to lane 6 of bay 3. The input code drop data indicating shift registers are also shifted as before. The drop program now is in the same state as step DP-21 above. A test is made for more drop data. Since there is none, the following step will occur:

FPS-14	)		FPS 14-15
DNIOP	)		

As data is not in output position (DNIOP), the functional programmer will go to step 15 as shown above. In this step of the drop program:

DP-22 MPS-7 FPS-15

the following functions will occur:

49. A decision will be made whether to go to FPS-18 or whether to go to FPS-16 or 17 before going to FPS-18. It will go to FPS-18 as follows:

FPS-15	)		FPS 15-18
NPRENB	)		

We now have the drop program step:

DP-23 MPS-7 FPS-18

in which the following functions occur:

50. Go to MPS-1.
51. Reset PRST (print start) set-reset memory.
52. Go to FPS-2.

We now have the drop program step:

DP-24 MPS-1 FPS-2

This will be recognized as the same as DP-3 wherein the tape reader advances the tape.

In the meantime, in the manner hereinbefore described, the rotating cam switch will fire one or two SCR's to generate drop pulses to energize drop solenoids L7 and L6 in select 2 and select 3 circuits in group MPX0 to drop an article from each of bays 2 and

3 simultaneously onto adjacent spaces on the conveyor.

In the manner hereinbefore described, the tape reader will read the leader and rubout codes and the next drop data (bay 0, lane 11) and will drop the lane 11 article in the space directly in front of the two filled spaces on the conveyor, the conveyor having advanced one increment since the two simultaneous drops were made.

SKIP DROP FOR ONE BELT INCREMENT

The programmers will then control the tape reader to read the next leader and rubout codes. However, conveyor spaces A, B and C will now be filled and since filled space C will be under bay 1, no dropping will take place for one belt increment.

Upon reading the rubout code, the mode programmer will advance to step 2 as in drop program step DP-6 above. We now have the condition:

DP-25 MPS-2 FPS-0

The functional programmer then recycles through steps 2 to 3 to 0 to read the leader code. Since drop data is not present (NOT TEDR), the mode programmer goes to step 7 as follows:

NOT TEDR	)		
Leader	)		
MPS-2	)		MPS 2-7

In this step, the functional programmer is set to step 10 as follows:

FPS-0	)		
)			FPS 0-10
MPS-7	)		

35 We now have the following drop program step:

DP-26 MPS-7 FPS-10

Since there is no drop data in the shift register output position, the functional programmer will go to step FPS-15, rather than step FPS-13 as before in drop program step DP-20, upon the occurrence of the pacer pulse as follows:

FPS-10	)		
DNIOP	)		
Pacer	)		FPS 10-15

From step FPS-15 the functional programmer will go to FPS-18 as hereinbefore described. This causes the mode programmer to go to MPS-1 under the conditions:

MPS-7	)		
FPS-18	)		
Auto Run	)		MPS 7-1

55 We now have the following drop program step:

DP-27 MPS-1 FPS-18

This causes the functional programmer to go to step FPS-2 under the conditions:

FPS-18	)		
)			FPS 18-2
MPS-1	)		

65 We now have the drop program step:

DP-28 MPS-1 FPS-2

This will be recognized as the same as step DP-3 and

DP-24 wherein the tape reader advances the tape. The functional programmer then cycles through step FPS-3 to FPS-0 as before to read another frame code. It will thus be apparent that the conveyor has advanced one increment without any dropping taking place. This is controlled by the tape so as to have the articles exit in the following order without any empty spaces on the conveyor:

Bay 0, lane 11 — A
Bay 2, lane 7 — B
Bay 3, lane 6 — C
Bay 1, lane 5 — D

The tape reader then continues advancing the tape as before to read the rubout code of the fourth record on the tape, causing the mode programmer to advance to step MPS-2 as follows:

MPS-1)
FPS-0)
Rubout) MPS 1-2

As hereinbefore described, the drop code shift registers in FIGS. 17a-b are cleared in MPS-1 and MPS-2. Also in MPS-2, the binary counter in FIG. 22b is cleared to zero condition preparatory to distributing shortage codes into the printer shift registers in FIGS. 22a-b. Also in MPS-2, the functional programmer is advanced to FPS-2 to advance the tape. The latter cycles from FPS-2 to FPS-3 to FPS-0 to read the "start of new order shortage data" code. This causes the mode programmer to advance to MPS-3 as follows:

MPS-2)
FPS-0)
NOSDC) MPS 2-3

The drop program is now in step:

DP-29 MPS-3 FPS-0

In this step, the functional programmer advances to step FPS-9 as follows:

MPS-3)
CC)
FPS-0)
Not Purge Complete) FPS 0-9

We now have the step:

DP-30 MPS-3 FPS-9

In this step, the "print enable" set-reset memory in FIG. 16, sh. 13 is set to 1 to enable printing of the shortage data soon to be read, and the functional programmer goes to step FPS-2 to read another frame.

The functional programmer now cycles from FPS-2 to FPS-3 to FPS-0 twice to read the bay 1, lane 5 drop code and to register it in the shift registers in FIGS. 17a-b as hereinbefore described.

The functional programmer then cycles again to read the five frames of the shortage code. When the first frame of the shortage code is read, the control codes logic in FIG. 13 produces shortage data signal SD. This causes the mode programmer to go to step MPS-5 as follows:

FPS-0)
MPS-3)
SD) MPS 3-5

This causes any shortage data in the printer shift registers in FIGS. 22a-b to be transferred to a buffer in the printer buffer, and causes the functional programmer to go from step FPS-0, where it read the first shortage code, to step FPS-4 as follows:

FPS-0)
MPS-5)
SD) FPS 0-4

10 We now have the drop program step:

DP-31 MPS-5 FPS-4 In this step, the first frame of shortage code bay 0 is parallel gated by signal FP54 and conductor PG into printer shift register PSR5 from the tape reader in FIG. 11 through conductors T1-8 to FIG. 22b. This gating is performed by the lowermost NAND logic in FIG. 22b and the second logic, AND, directly above it. This NAND logic receives a high signal from output 1 of the binary counter to provide a low signal to one input of the AND logic. The other input of the latter is gated by signal FPS4 to provide a parallel gating output signal PG to shift register PSR5. Also, the functional programmer goes to step FPS-5 as follows:

FPS-4)
DDSRO) FPS-5

The signal DDSRO is obtained from the "0" bit output of the drop data set-reset memory in FIG. 16 and indicates that the previously read drop data properly had a pair of codes. If the tape incorrectly contains an unpaired bay or lane code, that is, one frame only, an article will not be dropped in response thereto when the pacer pulse comes along, but instead dropping will be inhibited and later on when the corresponding conveyor space passes the photocell, a shortage code will be printed as hereinafter more fully described.

We now have the drop program step:

DP-32 MPS-5 FPS-5

This causes the binary counter in FIG. 22b to be advanced from zero to output 1(low) so that the next shortage code will go into printer shift register PSR-2.

45 The functional programmer now goes to step FPS-2 under control of the FPS-5 signal and cycles through FPS-3 to FPS-0 to read the second frame of shortage code, lane 11. It then goes to FPS-4.

In FPS-4, the second frame of shortage code is parallel gated into printer shift register PSR2 and, at the same time, the first code is transferred from printer shift register PSR5 to PSR1. As a result, the first two frames of code are now registered in proper order in printer shift registers PSR1 and PSR2.

The functional programmer then goes to step FPS-5 as before to advance the binary counter in FIG. 22b to output 2(low), outputs 1 and 4 having a high.

The functional programmer then cycles through steps FPS-2, FPS-3 and FPS-0 to read the third frame of shortage code, 98, and goes to step FPS-4 to register this code in printer shift register PSR5.

This cycle then repeats so that in the next binary counter step 3 outputs 1 and 2 having a low and output 4 having a high, the fourth shortage code is parallel gated into printer shift register PSR4 and, at the same time, the third shortage code is transferred from PSR5 to PSR3.

This functional programmer cycle then repeats once more to advance the binary counter to output 4 (low) and outputs 1 and 2 high and to register the last shortage code in printer shift register PSR5. Thus, the five frames of shortage code are now registered in printer shift registers PSR1-5 in the proper order.

The functional programmer then cycles through steps FPS-2, FPS-3 and FPS-0 to read the next frame of code which is a leader code.

The drop program then continues in the manner hereinbefore described and the drop data is processed in the logic system preparatory to dropping an article. In this process, when the functional programmer reaches step FPS-10, the LFS, look for shortage, set-reset memory is set to its 1 bit output in FIG. 16, preparatory to canceling the registered shortage code in the event the article exits. When the article thereafter interrupts the light beam, the photocell contacts in FIG. 7 close to provide a SPEC signal. This signal in FIG. 16, resets the SH, shortage, set-reset memory to cancel the shortage printing. This means that later on when the functional programmer reaches step FPS-15 in its normal operation as hereinbefore described, it will go to FPS-18 under the control of the NSHORTAGE signal, rather than going to FPS-16 under the control of a SHORTAGE signal as would be the case if an article did not exit.

SHORTAGE

If an article did not exit, the functional programmer would go from step FPS-15 to FPS-16 as follows:

FPS-15	)		FPS 15-16
PRENB	)		
shortage	)		

In this condition, the print start set-reset memory is set to 1 bit at output PRST in FIG. 16. Also, printer timer 62 is started in FIG. 9b to time a predetermined time interval. The printer in FIG. 22a operated to print the shortage code that is in the printer buffer. The timer allows a predetermined time for printing. If it takes longer, printer failure is indicated. Thus, if the functional programmer has not moved out of FPS-16 when the timer times out, it will go to FPS-17 to indicate printer failure. These signaling devices have not been shown to avoid complicating the drawings.

On the other hand, the functional programmer goes from step FPS-16 to FPS-18 as follows:

PRST	)		FPS-16-18
)	)		
FPS-16	)		

We now have the following drop program step:

DP-33   MPS-7   FPS-18

The mode programmer has moved to MPS-7 after having advanced the drop data to output position in the drop data shift registers in FIGS. 17a-b as hereinbefore described.

The mode programmer now goes to step MPS-1 followed by the functional programmer going to step FPS-2 to prepare the system for reading the next frame of code.

PURGE STOP

A purge stop is made by selecting this position on the selector switch in FIG. 7 while the system is running. In

this position, when the tape comes to the end of the present order (indicated by the "start of new order drop data" code of the next order), it will stop dropping articles but will continue to read tape in order to check shortages until the conveyor is completely purged of the articles on it, and then the tape reader will stop because the AUTO START signal is not on.

During a purge operation, in order to check out the articles already on the conveyor, or which should have been dropped but did not in the case of a shortage, the tape has to read ahead all the shortage data for the remainder of that order. When a restart is later made for the next order by pushing the AUTO START button, the tape will automatically back up to the correct position which consists of the six leader frames and will start the tape reading therefrom so that it can drop articles it had skipped during the process of looking ahead. At the beginning of this next order, the system will not look for shortages as to articles of the previous order that were purged or until articles for this next order begin to emerge from the storage area.

A detailed description of purge stop will now be given. Assuming that the selector switch in FIG. 7 is moved to PURGE position at the end of the fourth record on the tape in FIG. 3, the system will function as follows.

The tape reader will read the six frames of leader code and upon reading the rubout code, the mode programmer will go from MPS-1 to MPS-2. The functional programmer will cycle, causing the tape reader to read the "start of new order drop data" code. This will cause program advancement to MPS-3 and FPS-9 as hereinbefore described. This causes the purge execute set-reset memory in FIG. 7 to be set to PURGE EXC bit 1 under the conditions:

NODDC	)		
FPS-9	)		
Purge	)		PURGE EXC

40 This PURGE EXC signal is applied in FIG. 19 to inhibit the sink power output logics and prevent picking of a lane solenoid thereby to prevent dropping any articles. Normally this signal would also light an indicator lamp (not shown) to indicate that purge execute operation has started. Until such time, the operator is free to change his mind and return the selector switch in FIG. 7 to AUTO NOR. (automatic normal).

45 In this step, the purge complete set-reset memory is reset to NOT PURGE COMP state if it is not already therein.

The aforesaid functions are performed in the step.

DP-34   MPS-3   FPS-9

55 From FPS-9, the functional programmer immediately cycles through tape reader control steps FPS-2, FPS-3 to FPS-0 to read the next order drop data codes to no effect because dropping is inhibited, and to read the shortage data codes in the fifth record in FIG. 3. This shortage data will be registered in the printer shift registers in FIGS. 22a-b as hereinbefore described. This shortage data will be printed if a corresponding article does not exit past the light beam in FIG. 2, or will be canceled if the article does exit.

60 The logic system then functions in a similar manner to read the 6th record in FIG. 3, and the 7th record. This completes the purge execution which will be indicated when the tape reader reads the "start of new

this record. Shortages caused by this action will be printed later when the empty conveyor spaces pass the photocell detector of FIG. 2.

It will be recalled from the previous description, that the mode programmer goes from step MPS-0 to MPS-1 and the functional programmer goes from step FPS-0 to FPS-2 to start advancing the tape. The functional programmer then cycles through steps FPS-3 to FPS-0 to read each frame. Upon reading the rubout code, the mode programmer advances to MPS-2.

The mode programmer then goes to MPS-3 if a start of new order drop data code (NODDC) or a start of new order shortage data code (NOSDC) is read, and goes from there to MPS-4 upon reading drop data, bay or lane. On the other hand, the mode programmer goes from MPS-2 directly to MPS-4 if the code following the rubout code is a drop data bay or lane code. Also, the functional programmer goes to step FPS-6. We now have the condition:

MPS-4   FPS-6

Let it now be assumed that the lane code that should follow the bay code is missing. Since the drop data set-reset memory in FIG. 16 is in state DDSR0, the functional programmer will go to step FPS-7. This causes the drop data set-reset memory to be set in state DDSR1, and since there is no lane code, it will remain in this state.

The bay code will be loaded in the drop data shift registers and the functional program will cycle through steps FPS-2, FPS-3 to FPS-0 to read the next frame. This frame will be shortage data because the lane code is missing. This will cause the mode programmer to go to step MPS-5 under the conditions:

causing the functional programmer to go to step FPS-4 under the conditions:

FPS-0   }
MPS-5   }
SD   }   **FPS-0-4**

We now have the condition:

MPS-5   FPS-4

It should be noted that during the aforementioned operation following reading of the bay drop code, the drop data set-reset memory has been providing the DDSR1 signal. This signal is applied in FIG. 20 along with the MPS-5 signal to provide an inhibit signal DE. This inhibit signal is applied in FIG. 19 to prevent selection of any lane solenoid. Consequently, no dropping takes place as a result of the reading of the unpaired bay or lane record.

When the pacer pulse comes along from the rotary cam switch, the drop data cannot be loaded from the shift registers into the MPX because the functional programmer has remained in step FPS-4. This pacer pulse now causes the mode programmer to go to step MPS-1 as follows:

FPS-4   )
DDSR1   )
Pacer   )
)   **MPS-1**

as shown in FIG. 8. This causes the functional programmer to go to step FPS-0 under the conditions:

as shown in FIG. 9a.

The system is now in a condition to continue reading, but the error in the tape, productive of an unpaired bay 10 or lane condition, resulted in merely skipping a drop for this drop record.

SPACES BETWEEN CLASSES OF ARTICLES

The system has provision for purposely introducing spaces on the conveyor, for example, between different classes of goods. A "no print" code on the tape consisting of a hole punched in the T8 position controls this introduction of spaces.

Initially, a space on the conveyor would be left empty by a record having no drop code, such as the 3rd record in FIG. 3, or a record like this 3rd record but also including shortage data.

Thereafter, when this empty space would normally be checked for shortage, the corresponding record 25 would contain the aforesaid "no print" code having a hole in the T8 position.

When this code is read as the first frame of shortage data, it is applied to printer shift register PSR1 in FIG. 22a under the conditions:

30

T8)
SPLO)
MPSETS5) SDIP

35 T8 is the "no print" code; signal SPL0 is produced (adjacent printer shift register PSR5) since the binary counter is in zero position; MPSET5 is the concurrent input control to the mode programmer at this time; and the result SDIP is a signal meaning "shortage data inhibit print." This latter signal is inverted to provide a
40 not signal NSDIP to inhibit the printing coil under the conditions, in FIG. 22a:

FPS-16 is the functional program step when printing would normally be started, and NPRST is a signal from the present state of the "print reset" set-reset memory in FIG. 16.

50 Thus, the empty space on the conveyor, and consequent failure to interrupt the light beam to the photocell, will not cause a shortage to be printed.

The logic circuit in FIG. 22a also inhibits the printer on AUTO START so that it will not print whatever may be in the printer buffer. For this purpose, the combination of an AUTO START signal, from FIG. 7, and a NOT AUTO RUN signal from the corresponding set-reset memory in FIG. 16 are applied to this logic in FIG. 22a to produce an NSDIP signal to inhibit the PR coil.

If it is also desired to advance the printer tape one or two spaces at the place where spaces were introduced on the conveyor, a different code having holes punched in the T4 and T8 positions is used in place of one or two of the T8 codes above. This code is read in the same way and is applied directly to printer shift register PSR1 under the following conditions:

T8	)	
SPL0	)	
T4	)	

PSR1

Then, MPSET5 signal shifts this code into the printer buffer to provide signals SDIP and PPS. These signals gate the logic in FIG. 22a during functional program step FPS-16 (when printing would normally be initiated) to space the printer by advancing its tape one space. One or two of these spaces may be introduced on the printer tape to aid in visually finding the division between different classes of articles. At the same time, the NSDIP signal inhibits printing of a shortage for the deliberately introduced space on the conveyor

While the apparatus hereinbefore described is effectively adapted to fulfill the objects stated, it is to be understood that the invention is not intended to be confined to the particular preferred embodiment of tape controlled order picking system disclosed, inasmuch as it is susceptible of various modifications without departing from the scope of the appended claims.

We claim:

1. In an order picking system for a warehouse having a storage area including a plurality of article-storing lanes, and a conveyor having defined spaces for receiving articles released from the lanes and for conveying them to a collection station, the combination comprising:

an article release device for each lane; 30
synchronizing control means operable in time with the article conveyor for providing timing signals; and an electrical system under the control of said timing signals for releasing articles into the defined spaces comprising:

a code bearing medium having article picking codes thereon arranged to control selection of lanes and release of articles for exit in a controlled order, and having system control codes;

means for reading said codes from said medium in sequence;

a register for registering said article picking codes; logic circuits for recognizing said system control codes and for providing control signals in response thereto;

program control means;

means for initiating operation of said system; means responsive to said initiation of operation of said system and said timing signals and control signals for operating said program control means to

control said code reading means to intermittently read the article picking codes and corresponding system control codes relating to each article to be released and to store each article picking code in said register pending use thereof for lane selection; 55

means responsive to said timing signals, system control codes and said program control means for transferring each article picking code from said register to select the lane identified thereby;

and means responsive to said timing signals for energizing the article release device of the selected lane thereby to release an article into a defined space on the conveyor.

2. In an order picking system for a warehouse having a storage area including a plurality of article-storing lanes, and a conveyor having defined spaces for receiving articles released from the lanes and for conveying

them to a collection station, the combination comprising:

an article release device for each lane; synchronizing control means operable in time with the article conveyor for providing timing signals; and an electrical system under the control of said timing signals for releasing articles into the defined spaces comprising:

a code bearing medium having article picking codes thereon arranged to control release of articles for exit in a controlled order, and having system control codes;

means for reading said codes from said medium in sequence;

a register for registering said article picking codes; logic circuits for recognizing said system control codes and for providing control signals in response thereto;

program control means;

means for initiating operation of said system;

means responsive to said initiation of operation of said system and said timing signals and control signals for operating said program control means to control energization of said article release devices to release articles into the defined spaces in accordance with said article release codes;

said code bearing medium also having shortage codes spaced thereon so as to be read at times when released articles are supposed to be passing an exit point and the last shortage codes of a given order overlapping on said medium with respect to first article picking codes of the next order;

an article detector at said exit point;

means operable when said article detector does not detect an article corresponding to a shortage code for recording a shortage indication;

and said electrical system also comprising a purge logic circuit for controlling completion of an order of articles by checking shortages followed by stopping the system without releasing articles from the next order appearing in overlapping relation on said code bearing medium.

3. In an order picking system for a warehouse having

a storage area including a plurality of article-storing lanes, and a conveyor having defined spaces for receiving articles released from the lanes and for conveying them to a collection station, the combination comprising:

an article release device for each lane; synchronizing control means operable in time with the article conveyor for providing timing signals; and an electrical system under the control of said timing signals for releasing articles into the defined spaces comprising:

a code bearing medium having article picking codes thereon arranged to control release of articles for exit in a controlled order, and having system control codes;

means for reading said codes from said medium in sequence;

a register for registering said article picking codes; logic circuits for recognizing said system control codes and for providing control signals in response thereto;

program control means;

means for initiating operation of said system;

means responsive to said initiation of operation of said system and said timing signals and control signals for operating said program control means to control energization of said article release devices to release articles into the defined spaces in accordance with said article release codes; 5
said synchronizing control means comprising:
a pulse generating device for generating article release pulses for the conveyor increments during which the defined spaces are passing by lanes to cause release of the articles from the selected lanes; 10
and said pulse generating device also generating a pacer pulse for each conveyor increment to control the time when the registered article release code is used to select an article release device of a particular lane which release device is thereafter energized by an article release pulse. 15
4. The invention defined in claim 3, wherein said pulse generating device comprises:
means for generating a plurality of time-spaced article release pulses for each conveyor increment to enable preselection of the instant of article release with respect to passage of the defined space to insure that the article will enter said defined space. 20
5. In an order picking system for a warehouse having a storage area including a plurality of article-storing lanes, and a conveyor having defined sequential spaces for receiving articles released from the lanes and for conveying them past a shortage detecting point to a collection station; the combination comprising:
an article release device for each lane; 25
synchronizing control means operable in time with the article conveyor for providing timing signals; and a logic system under the control of said timing signals for controlling the release of articles from the lanes so as to fill all the conveyor spaces comprising:
a code bearing medium having a plurality of successive predetermined records thereon; each such record including an article release code and/or an article shortage code and control codes for controlling the system program; 30
a code reader for reading the codes of a record in sequence; 40
an article release code register for registering each article release code when it is read; 45
an article shortage code register for registering each article shortage code when it is read; 50
a shortage printer;
logic circuits for recognizing said control codes and for providing control signals in response thereto; 55
a programmer in said logic system;
means for initiating operation of the system; 60
means operable upon said initiation of operation for operating said logic system including said programmer under the control of said control signals, article release codes and timing signals to energize said article release devices; 65
an article detector at an exit point;
means operable when said article detector fails to detect an article at a time when an article that was scheduled for release should be passing thereby for setting in said programmer a shortage printing sequence causing transfer of the article shortage code from its register to said shortage printer and

for operating the latter to print the shortage code that identifies the missing article; and means operable when said article detector detects an article for causing said programmer to skip said shortage printing sequence. 5
6. The invention defined in claim 5, wherein said logic system also comprises:
a purge logic circuit for controlling shortage checking of the remaining released articles of an order without releasing any articles of the subsequent order whose article release codes may overlap the remaining shortage code records of the present order; 10
a manual selector switch for transferring said system from normal automatic operation to purge operation thereby to cause said purge logic circuit to provide a purge execute signal when a control code indicative of start of a new order release code is recognized by said control codes recognizing logic circuits; 15
and means in said system responsive to said purge execute signal for inhibiting release of any articles for the new order. 20
7. The invention defined in claim 6, wherein said purge logic circuit comprises:
means for providing a purge complete signal when a control code indicative of start of a new order shortage code is recognized by said control codes recognizing logic circuits; 25
and means in said system responsive to said purge complete signal for setting said programmer to stop the reading. 30
8. The invention defined in claim 7, wherein said logic system comprises:
means responsive to said purge complete signal upon reoperation of said means for initiating operation of the system for setting said programmer to cause reversal of said tape reader to a point ahead of the beginning of said new order release codes followed by normal forward operation of said tape reader to read the new order release codes. 35
9. The invention defined in claim 5, wherein said logic system also comprises:
a record on said medium wherein the article release code is omitted whereby an empty space is deliberately introduced on the conveyor to separate different classes of articles; 40
and said control codes include a no-print code in the record corresponding to the exit of said empty space past said article detector; 45
and means responsive to said no-print code for inhibiting the printer. 50
10. The invention defined in claim 9, wherein said logic system further comprises:
an advance-printer-tape code combined with said no-print code; 55
and means responsive to said advance printer tape code for advancing the printer tape one normal printing space to provide a visual gap indication of where the different classes divide. 60
11. In an order picking system for a warehouse having a storage area including a plurality of bays each having a plurality of gravity-feed article-storing lanes, and a conveyor having sequential spaces defined by pushers with each space being a conveyor increment that is a function of the width of a bay so that one lane

per bay can drop an article into a defined space at a time, the combination comprising:

an article-drop device for each lane;
 a synchronizing switch operable in time with conveyor travel to provide a pacer pulse and a drop pulse during each conveyor increment;
 and a logic system including a programmer under the control of said pulses for controlling the drop of articles from the lanes so as to fill all the conveyor spaces comprising:
 a punched tape having a plurality of successive, programmed, records thereon, each record including control data and article drop data and article shortage data, with the article drop data at the beginning of a second order overlapping shortage data at the end of the previous order as to at least some of the tape records between the two orders, each drop data consisting of at least one code having a frame of bay code followed by a frame of lane code constituting a paired bay and lane code;
 a code reader for reading the frames of code of a record in sequence;
 a drop data shift register for receiving the bay and lane codes from the code reader;
 a shortage data shift register for receiving the shortage data codes from the code reader;
 a shortage printer;
 logic circuits for recognizing said control data and providing control signals corresponding thereto;
 means operable at will for initiating operation of said system;
 means responsive to said initiation of operation for operating said logic system including said programmer under the control of said control data, paired bay and lane code, pacer pulse and drop pulse to select and energize the selected article drop device;
 a shortage detector at an exit point;
 and means operable when said shortage detector detects or fails to detect an article under the control of said pacer pulse for inhibiting printing or print-

ing, respectively, the shortage code that was previously registered in said shortage data shift register.

12. The invention defined in claim 11, wherein said logic system including said programmer comprises:
 means for detecting the reading of an unpaired bay or lane code;

and means responsive to said detecting means for controlling said programmer to skip the dropping program for that record and for causing the tape reader to continue with reading the next record.

13. The invention defined in claim 11, wherein said logic system including said programmer comprises:
 an inhibit logic circuit for recognizing a bay or lane code that is higher in value than the warehouse capacity and for providing an inhibit signal in response thereto;
 and means responsive to said inhibit signal for preventing the generation of a drop pulse for the corresponding tape record.

14. The invention defined in claim 11, wherein said control data on said punched tape comprises:
 a first frame of control code indicative of the start of each record;
 a second frame of control code indicative of the end of each record;
 means in said logic system under the control of said first frame of control code for setting said programmer to control reading of the remainder of the data in the corresponding record;
 and means in said logic system under the control of said second frame of control code for setting said programmer to control processing of the drop data read from the corresponding record.

15. The invention defined in claim 14, wherein:
 a record on said punched tape consists of said first frame of control code immediately followed by said second frame of control code when dropping of an article is to be skipped for the corresponding conveyor increment.
